BUTTONHOLE CONSTRUCTION

Max J. Isaacson, Brooklyn, N. Y.

Application May 8, 1948, Serial No. 25,855

3 Claims. (Cl. 2—243)

1

This invention relates to new and useful improvements in the construction of buttonholes in garments.

A main object of the invention is to provide a simple, economically constructed buttonhole structure for a garment which will permit the button to be inserted and removed with ease and with a minimum of wear and tear on either the thread connecting the button to the garment or on the buttonhole structure itself.

Further and more specific objects, features and advantages will more clearly appear from a consideration of the detailed specification hereinafter set forth, especially when taken in connection with the accompanying drawings which illustrate a present preferred form which the invention may assume and which form part of the specification.

In brief and general terms, the invention includes at least two layers of material one of which is provided with an angular buttonhole, the two layers being joined together along one side only of said hole.

Preferably the hole is triangular and the layers are joined together along one side thereof above the base of the opening.

More particularly, the construction permits the button to be slipped down between the two layers at the base of the opening and then slipped to one side between said layers. When the button is to be removed, since the layers at the opposite side of the opening are sewed or joined together, the button will ride over these joined edges and emerge with its upper half above the base line of the opening whereupon it can be moved vertically from the hole entirely with practically no wear and tear on the hole or on the threads connecting the button to the garment.

More particularly, the corner of the hole toward which the button is moved, when inserted, is provided with a depressed pocket to more firmly locate the button therein.

The present preferred form which the invention may assume is illustrated in the drawings, of which—

Fig. 1 is a rear elevation, with portions broken away, of a part of a garment showing a series of buttonholes of my improved form;

Fig. 2 is an enlarged partial rear elevation of one buttonhole;

Fig. 3 is a horizontal cross section taken on the line 3—3 of Fig. 2;

Fig. 4 is a horizontal cross section taken on the line 4—4 of Fig. 1;

2

Fig. 5 is a cross section taken on the line 5—5 of Fig. 1; and

Fig. 6 is a vertical cross section taken on the line 6—6 of Fig. 2.

Referring now to the specific form of the invention shown in the drawings, which is only one form which the invention may assume, it is to be seen that the area of the garment where are located the buttonholes is formed of two main layers of material 10 and 11 constituting the respective front and rear layers thereof. Disposed between these layers 10 and 11 (see Figs. 1 and 3) and reading from layer 11 to layer 10 are a stiffening layer 12, a reinforcing layer 13, and a layer 14 forming the rear wall or backing layer of the buttonhole opening.

The shape of the hole cut in the layers 11, 12 and 13 is angular and preferably somewhat triangular with an elongated base portion 15, a curved sloping left side 16, and a sharply sloped substantially straight right side 17 (as viewed in Fig. 2). As seen in the drawings, the layers 11, 12, 13, and 14 are sewed together along the length of the left side 16 as seen in Fig. 3, but along the base 15 and the right side 17 only the layers 11, 12, and 13 are sewed together. The button, shown in dotted lines in Fig. 1 has a semi-diameter just short of the height of the apex of the buttonhole opening. It is apparent that the button, on introduction, may be moved down between the two layers 11 and 14 along the base side 15 and then may be moved to the right to dispose its axis in the right corner of the angular opening, since the two layers 11 and 14 along the right side 17 are not connected. In removing the button it is merely necessary to move it to the left, whereupon, since the two layers 11 and 14 are connected along the left side 16, the left edge of the button will ride up over these joined edges and its upper half will emerge into view, after which it can be moved vertically to remove its lower half from between the layers 11 and 14 below the base edge 15. It is of course to be noted that in reality we need only the two layers 11 and 14 to achieve the effect of the invention, since the layers 12 and 13 are merely introduced to make a more durable and finished product. It is also to be noticed that the right hand corner of the buttonhole slopes downwardly to form a sort of depressed pocket 18 into which the threads connecting the button to the other side of the garment may lie when the button is in inserted position.

As shown in Fig. 5, the button is sewed to a layer of cloth 19 forming the other side of the

55

front of the garment. The layer 10 is the front of the garment on the buttonhole side. It will be seen that this construction will permit of the easy and rapid insertion and removal of the button with a minimum of wear and tear on the buttonhole and on the threads connecting the button to the garment. The layers of material 12, 13, and 14 are shown as extending integrally all along the garment back of the series of buttonholes, although it is to be noted that they 10 may, if desired, be only used in the area immediately around the buttonholes.

While the invention has been described in detail and shown with respect to the accompanying drawing, it is not to be limited to such details, since many changes and modifications may be made in the invention without departing from the spirit and scope thereof. Hence, it is desired to cover any and all forms and modifications of the invention which may come within the language and scope of any one or more of the appended claims.

What I claim as my invention is:

1. A garment construction which includes four layers of material, three adjacent layers having formed therein aligned angular buttonholes, the four layers being joined together along one side of said angular opening, the three adjacent layers being joined together along the other sides of the angular opening.

2. A garment construction which includes four layers of material, successively a main layer, a stiffening layer, a reinforcing layer, and a backing layer, the first three layers being formed with aligned buttonholes of triangular shape, the fourth layer extending across said holes, the

15

20

first three layers being joined together around two sides of said holes, and the four layers being joined together around the third side of said holes.

3. A garment construction which includes four layers of material, successively a main layer, a stiffening layer, a reinforcing layer, and a backing layer, the first three layers being formed with aligned triangular buttonholes therein, the base of said holes being flat, one side above the base being curved and the other side above the base being sharply sloped downward in a substantially straight line, the junction of the base and the latter side joined to form a slightly depressed button-thread receiving pocket, the fourth layer extending across said holes, the first three layers being joined together around the base and straight side of the holes, and the four layers being joined together around the curved side of the holes.
